(57) **CLAIM**

The ornamental design for a silicone oven mitt and pot holder with pocket set, as shown and described.

DESCRIPTION

FIG. 1 is a perspective view of a silicone oven mitt of a silicone oven mitt and pot holder with pocket set, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is a perspective view of a pot holder with pocket of the silicone oven mitt and pot holder with pocket set, shown separately for ease of illustration;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is an enlarged view of portion 18 shown in FIG. 11; and,

FIG. 19 is a perspective view of the silicone oven mitt and pot holder with pocket set, shown in use with the silicone oven mitt working with the pot holder with pocket.

The dash-dash broken lines in FIGS. 1-18 depict portions of the silicone oven mitt and pot holder with pocket set and form no part of the claimed design. The additional dash-dash broken lines in FIG. 19 depict environment and form no part of the claimed design. The dash-dot broken lines demarcate the enlarged views and form no part of the claimed design.
